US00D760332S

(12) **United States Design Patent**
Black, Jr. et al.

(10) **Patent No.:** **US D760,332 S**
(45) **Date of Patent:** **** Jun. 28, 2016**

(54) **GOLF TEEING DEVICE**

(71) Applicant: **TEE-CLAW LLC**, Tustin, CA (US)

(72) Inventors: **John Luther Black, Jr.**, Costa Mesa, CA (US); **John Efrin Candias**, Newport Beach, CA (US)

(73) Assignee: **Tee Claw LLC**, Tustin, CA (US)

(**) Term: **14 Years**

(21) Appl. No.: **29/514,758**

(22) Filed: **Jan. 15, 2015**

Related U.S. Application Data

(63) Continuation of application No. 14/579,164, filed on Dec. 22, 2014, which is a continuation-in-part of application No. 13/918,027, filed on Jun. 14, 2013, now Pat. No. 8,968,118.
